United States Patent Office

Des. 193,011
Patented June 12, 1962

193,011

GOLF CLUB CARRIER

Leroy Alston, 2253 Pleasant Ave., Hamilton, Ohio

Filed Dec. 1, 1961, Ser. No. 67,773

Term of patent 14 years

(Cl. D34—5)

FIG. 1.

FIG. 2.

FIG. 3.

I claim:

The ornamental design for a golf club carrier, as shown.
